CLAIM

The ornamental design for a child swing motor housing and frame, as shown and described.

DESCRIPTION

FIG. 1 is a perspective view of a child swing motor housing and frame showing our new design; the broken line showing of swing and handle is for illustrative purpose only and forms no part of the claim;

FIG. 2 is a front elevational view thereof;

FIG. 3 is a left-side elevational view thereof;

FIG. 4 is a right-side elevational view thereof;

FIG. 5 is a rear elevational view thereof; and,

FIG. 6 is a top plan view thereof.

FIG. 4

FIG. 5

FIG. 6
